UNITED STATES PATENT OFFICE.

DANIEL W. CARTWRIGHT, OF DETROIT, MICHIGAN.

EMERY-WHEEL GUARD.

1,160,841.

Specification of Letters Patent. Patented Nov. 16, 1915.

Application filed September 15, 1915. Serial No. 50,733.

To all whom it may concern:

Be it known that I, DANIEL W. CARTWRIGHT, a citizen of the United States of America, residing at Detroit, in the county 5 of Wayne and State of Michigan, have invented certain new and useful Improvements in Emery-Wheel Guards, of which the following is a specification, reference being had therein to the accompanying drawings.

10 As a "safety first" factor and guard for workman in the vicinity of a driven emery wheel, casings have been designed and used to prevent broken fragments or pieces of a bursted emery wheel from injuring work- 15 man or persons in proximity to the wheel, such casings also possessing certain characteristics among which may be mentioned that of adjustment for keeping the casing in proper position relative to the periphery 20 of a wheel whereby the wheel can be used; that of preventing water from flying from the periphery of the wheel, and that of preventing the escape of water from the casing through that side which receives the shaft 25 for revolving the wheel. A casing in accordance with my invention possesses all of the above characteristics and also includes a simple, durable and inexpensive closure for that side of the casing through which the 30 wheel shaft or arbor extends, said closure having a novel adjustment which permits of the grinding opening of the casing being retained in proper relation relative to the exposed periphery of the grinding wheel.

35 The mechanical construction of my improved emery wheel casing will be herein-after described and then claimed, and reference will now be had to the drawings, wherein

40 Figure 1 is an elevation of one side of the casing, showing my improved closure; Fig. 2 is a front elevation of the same, partly broken away, showing sectional details on or about the line II—II of Fig. 1; and Fig. 45 3 is an elevation of the opposite side of the casing from that shown in Fig. 1.

The safety guard comprises a cylindrical metallic casing 1 having a closed side or wall 2, an open side 3, a peripheral grinding opening 4, a rearwardly extending tangentially disposed discharge spout 5, and a slotted web 6 to facilitate attaching the casing to a suitable support. The casing is also provided with peripheral apertured lugs 7 contiguous to the open side 3, and detachably connected to said lugs, by screw bolts or

other fastening means, is a side plate 8 having an oblong or oval offset portion 9 providing clearance for the inner end of a shaft or arbor 10 supporting an emery or 60 grinding wheel 11 within the casing.

The closed side or wall 2 of the casing has an eccentric opening 12 provided with an annular inset seat 13 for a circular rotatable side plate 14. To hold said plate upon the seat 13, the wall 2 is provided with opposed adjustable clips 15, and to facilitate the rotating of said plate there is a knob 16 on the outer side of said plate adjacent the periphery thereof. 70

The side plate 14 has an eccentric opening 17 provided with an annular seat and clips for another side plate 18, which has a knob 19. The annular seat and clips of the side plate 14 are similar to the annular seat and clips of the wall 2, said seats and clips constituting means for holding the plates 14 and 18 in an adjusted position relative to the casing. 75

The small plate 18 has an eccentric opening 20 and the outer side of said small plate also has a seat 21 for a flat ring or collar 22 which encircles the shaft or arbor 10. The ring or collar 22 is preferably made of felt or a yieldable material and while preventing water or detritus from passing through the opening 20, it also compensates for any inequality between the shaft 10 and the casing 1. 80

It is through the medium of the large and small eccentrically disposed plates 14 and 18 that adjustment can be made to properly position the emery or grinding wheel 11 relative to the casing 1, whereby the periphery of the emery or grinding wheel will be exposed at the grinding opening 4 of the casing. These adjustments are made as the diameter of the emery or grinding wheels decreases by wear, and the novel closure cooperates with the oval offset portion 9 of the 90 detachable side wall 8 in providing clearance for the shaft or arbor 10. The detachable side wall 8 permits of the emery or grinding wheel being easily installed and adjustments of the closure can be quickly 95 100 accomplished. 105

One embodiment of my invention has been illustrated, but it is to be understood that the structural elements are susceptible to such variations and modification as fall 110 within the scope of the appended claims.

What I claim is:—

1. An emery wheel casing having a wheel shaft extending through a side wall thereof, and plates eccentrically disposed relative to each other permitting of adjustment of said wheel shaft relative to said casing.
2. An emery wheel casing having a wheel shaft extending through a side wall thereof, plates eccentrically disposed relative to each other in a side wall of said casing permitting of adjustment of said wheel shaft relative to said casing, and means adapted to hold said plates in adjusted position.
3. An emery wheel casing having a wheel shaft extending through a side wall thereof, plates eccentrically disposed relative to each other and to said casing permitting of ad-

justment of said wheel shaft relative to said casing, and a flexible collar carried by one of said plates and encircling said wheel shaft.

20

4. A guard for grinding wheels supported by a shaft, comprising a casing having an offset portion providing clearance for an end of said shaft, and a closure having adjustable rotary plates permitting of adjustment of said shaft relative to said casing.

25

In testimony whereof I affix my signature in presence of two witnesses.

DANIEL W. CARTWRIGHT.
